UNITED STATES PATENT OFFICE

JOSEPH WEINSTEIN, OF BROOKLYN, NEW YORK, ASSIGNEE TO DEVICE EQUIPMENT CORPORATION, OF NEW YORK, N. Y., A CORPORATION OF DELAWARE

REFRIGERATORY CONTAINER

Application filed June 22, 1927, Serial No. 200,515. Renewed March 21, 1930.

This invention relates generally to containers but more particularly to a unique and novel refrigeratory container.

One of the objects of the invention is the provision of a combined refrigerant container and refrigerator chamber with special reference to the small or portable type.

Another object is to provide a unit of the above type that permits of free and easy access to the interior of both chambers.

Another and more specific object is to provide a container of the vacuum type, embodying the above features, and one that may be used in a manner to utilize the full advantages 15 of the vacuum or when not in use to compact the unit by collapsing the vacuum providing section.

Another object is the provision of a convertible refrigeratory container in which the refrigerant either surrounds the refrigerator

chamber or is surrounded by it, as desired. A still further object is to provide a refrigeratory container of the above type peculiarly adapted to use solid carbon dioxide as 25 the refrigerant.

It will be apparent by reference to the following specification and claims taken in connection with the accompanying drawings how I attain these and other objects, which are brought out more fully hereinafter.

Referring to the accompanying drawings,

Fig. 2 is a horizontal section taken on the line 2-2 of Fig. 1:

Fig. 3 is a fragmentary vertical section taken on the line 3—3 of Fig. 2 and

Fig. 4 is a slight modification of the refrigeratory container shown minus the vacuum providing section.

The numeral 1 indicates a preferred type of container having an outer air tight casing made of any suitable material such as rubberized fabric or any other air tight material, 45 possessing as one of its main qualities a substantial extent of flexibility and consisting preferably of an outer layer 2 and an inner layer 3, the outer layer acting more in the nature of a protective covering although they 50 both should be air tight.

Attached to the inner side 3 are the vertical strips 4 preferably extending for substantially the height of the outer casing and having pivotally connected thereto, at spaced intervals, one end of the springs 5, the other end of said springs being pivotally connected to the container 6. These springs are here shown as being made of flat material and U shaped; however any type of spring suitable for the purpose may be used. 65

Within the container 8 and preferably made integral therewith is the container 7, which generally would be used as the refrigerant container and placed as shown within the container provided to hold the liquid or gas material to be refrigerated.

This construction provides the vacuum space 8, refrigerator chamber 9 and refrigerant container space 10.

One end of the container 7 has the opening 11 therein to allow for access to the interior thereof and a screw threaded or other suitable plug 12 is provided to close the entrance 11 and to hold the refrigerant therein. Carbon dioxide gas sublimed from the solidified carbon dioxide within the refrigerant container will escape by the plug or through any conventional opening as shown at 13.

It is well known that carbon dioxide gas is quite difficult to maintain within an enclosure or container unless particular efforts are made to make the container gas tight, and unless the plug is very accurately fitted to the opening, the carbon dioxide gas will escape therefrom, thus obviating the necessity for a positive vent. However, I have shown a conventional vent through the plug itself. The plug 11 can be of any suitable type either being threaded or held in place by wedging.

In one end of the container 6, preferably at the end opposite the opening 11 is an opening 14 to permit of access to the chamber 9, and has any suitable closure 15, either threaded or otherwise, covered by the outer cover 17 which is made in the form of a cup and may be used for drinking purposes.

The straps 18 are provided to hold the vacuum section in collapsed position against tension of the springs 5.

Fig. 3 is a fragmentary section, on an enlarged scale, showing the structure of the upper part of the upper layer of the upper bed of the Lower Cretaceous.

larged scale, taken on the line 3—3 of Fig. 2 and shows the layers of fabric 2 and 3 with the strips 4 attached thereto and the spring 5, one end of which is attached to the strip 4 and the other end to the container 6, the strips 4 are preferably metallic but may be made of any suitable material and the springs 5 may be attached to these strips and the container 6 in any suitable manner.

10 The operation of the device is simple and obvious, being as follows:

The plug 12 is removed and the solid carbon dioxide in the desired quantities is placed within the container 7, the plug then being 15 replaced. The liquid or material to be refrigerated is placed within the container 6 through the opening 14. The air has previously been exhausted from the space 8 and the same hermetically sealed, thus providing 20 a vacuum around the longitudinal walls of the container 6, the springs 5 normally urging the outer casing to extended position.

When it is desired to compact the unit, 25 pressure may be applied against the springs, thus collapsing the outer casing and the same may be held in collapsed position by means of the straps 18.

At times it may be desirable to supply a 30 larger amount of refrigerant than the capacity of the container 7, this might come about when one is travelling and needs to have a charge of refrigerant that will last an unusually long time, or it might be desirable to refrigerate the product to a lower temperature 35 than is normally required or even to freeze the same, in such case the container 7 may be converted to a refrigerator chamber and the container 6 converted to a refrigerant container.

40 From the above it will be seen that I have provided an efficient, simple and compact unit in which may be embodied the vacuum principle for supplying heat insulation and at the same time a simple and inexpensive structure 45 in which may be utilized the unusual refrigerating qualities of solid carbon dioxide. I have also supplied a refrigeratory container in which neither the refrigerant nor the gas therefrom comes in contact with 50 the material to be refrigerated.

Fig. 4 is a slight modification disclosed without the outer vacuum providing casing which may or may not be placed thereon. In 55 this modification the entrances to both the refrigerant container and refrigerator chamber are in the same end of the unit. This form is particularly adaptable in the larger refrigeratory containers especially of the water bottle type. The bottle 1b has the 60 opening 2b therein and the refrigerant container 3b located therein, the entrance 4b of the container 3b being closed preferably by screw threaded plug 5b and is shown as having 65 therein the conventional vent 6b. This construction is more applicable to the type

that requires to be charged, either with a refrigerant or material to be refrigerated generally only once a day, it is especially adaptable in place of the ordinary large water bottle. If it is desired to maintain a 70 very low temperature within the container 1b, the same form of outer vacuum providing means, as shown in Figs. 1, 2 and 3 may be applied.

While the forms I have disclosed are preferable, nevertheless any number of changes or modifications might be made without departing from the spirit or scope of the invention and I do not mean to be limited to the specific structures here shown.

Having thus described my invention, what I claim as new and desire to secure by United States Letters Patent is:

1. In a device of the class described, the combination with an exterior collapsible container, of an interior bottle connected with the container, inverted U-shaped springs pivotally connected at one end to the bottle, metallic strips secured to the inner sides of the container, and the other ends of the springs being connected to the metallic strips, to normally urge the collapsible container into open condition.

2. In a device of the class described, the combination with an interior bottle, of an exterior collapsible container hermetically connected therewith and presenting a vacuum therein, springs for normally urging the collapsible container into open position, and straps secured to the said collapsible container and arranged for holding the collapsible container in collapsed position.

3. A device of the class described, comprising an interior bottle, an exterior collapsible container hermetically connected therewith and presenting a vacuum therein, a means for normally urging the collapsible container into open position, and a means arranged for holding the collapsible container in collapsed position.

4. A device of the class described, comprising a container adapted for holding liquids and provided with a chamber arranged for holding a refrigerant, this chamber being integral with and formed within the outer surface of the container, and a second container hermetically sealed and presenting a vacuum therein, surrounding and attached to the said container, together with an exterior protective casing for said second container.

5. A device of the class described, comprising a container adapted for holding liquids and provided with a chamber arranged for holding a refrigerant, this chamber being formed within the outer surface of the container, and accessible thru the bottom of the container, said container being arranged for providing accessibility to the interior thereof thru the top, and a second container hermetically sealed and presenting a vacuum

therein, surrounding and attached to the sides of the container.

6. A container of the vacuum type comprising an inner refrigerant container, an outer container surrounding said inner refrigerant container and adapted to contain the material to be refrigerated, and a collapsible outer casing surrounding said outer container, said outer casing being arranged to maintain a vacuum around said outer container.

10. A container of the vacuum type comprising a refrigerant container and a refrigerated chamber, said refrigerant container and said refrigerated chamber being made integral and an outer collapsible casing adapted to maintain a vacuum around said integral structure.

15. In testimony whereof I have affixed my signature.

JOSEPH WEINSTEIN.
